COMBINATION JUICE COOLER AND DISPENSER

Pierre Masson, Los Angeles, Calif., assignor, by mesne assignments, to Dispensers, Inc., Los Angeles, Calif., a corporation of California

Application October 31, 1955, Serial No. 38,638

Term of patent 14 years

(Cl. D2—3)

Fig. 1.

Fig. 2.

Fig. 1 is a perspective view of a combination juice cooler and dispenser embodying my new design and showing the top, front and one side thereof, and Fig. 2 is a perspective view showing the top, back and other side thereof.

The characteristic features of my design for the combination juice cooler and dispenser disclosed reside in the front thereof having the configuration and appearance shown.

I claim:

The ornamental design for a combination juice cooler and dispenser, as shown and described.
